(57) **CLAIM**

The ornamental design for a floor stand for a light therapy device as shown and described.

DESCRIPTION

1. Floor stand for a light therapy device

1.1 : Perspective

1.2 : Front

1.3 : Back

1.4 : Left

1.5 : Right

1.6 : Top

1.7 : Bottom

1.8 : Perspective

A new and original design for a floor stand for a light therapy device comprises a base with a top side having a mounting recess positioned centrally thereon, a pair of first planar surfaces extending outward therefrom and a pair of second planar surfaces extending at an angle with the first planar surfaces, wherein the base is coupled to a generally upright first mounting channel proximate to a left end of the mounting recess and a generally upright second mounting channel proximate to a right end of the mounting recess.

1 Claim, 8 Drawing Sheets
